11 Claims. (CL 196—16)

My invention relates to a method for purifying non-aqueous liquids and more particularly to the method of purifying mineral hydro-carbon oils.

According to my present invention the non-aqueous liquids, such as mineral hydro-carbon oils, are treated to render them anhydrous and free from dissolved gases, moisture and other foreign matter.

In accordance with one aspect of my process in the treatment of mineral hydro-carbon oils which have insulating value in electrical apparatus, I treat the oils for freeing them of moisture or any foreign ingredients resulting from oxidation of the oil when in use. In the purification of mineral hydro-carbon oils, my present invention is applicable both to the conditioning of new oils, and the reconditioning of oils after use. Mineral hydro-carbon oils are adaptable for many purposes among which are lubrication purposes and electrical insulation purposes. In that type of oils used for electrical insulation purposes, the oils are used both as a cooling and insulating medium in the transformers and voltage regulators, and as an insulating medium in cable joints and the like. After considerable use for these purposes, the oils are subjected to oxidation, resulting from the combined action of heat absorbed from the apparatus, and the oxygen in the atmosphere which has access to the oil, resulting in the formation of organic acids, volatile hydro-carbons and sludges. In the use of these oils in the circuit breakers, the arcing action which takes place decomposes the hydro-carbons and considerably reduces the dielectric strength of the insulating medium. Concurrently with the partial decomposition of the oil, water or moisture is formed. These traces of water may be in true solution in the oil and that, with the evolved carbon particles of colloidal or suspended size, contribute to the deterioration of the insulating action of the oil.

In accordance with one aspect or phase of my process, I treat non-aqueous liquids including oils, and particularly including electrical insulating oils to render them moisture free.

In another aspect of my invention I filter these non-aqueous liquids, including oils and particularly electrical insulating oil, to render them free of carbon particles or other suspended foreign matter. In accordance with my improved process, the treatment to render the non-aqueous liquids free from moisture may be carried out irrespective of the filtering operation, or, if desired, may be carried on either successively or simultaneously with the filtering operation.

In accordance with the broad features of my invention for rendering the non-aqueous liquids free from moisture, I introduce the non-aqueous liquids under pressure in very finely divided condition into a vacuum chamber from which the air and other gas is excluded, and which is maintained under a relatively high degree of vacuum. The non-aqueous liquid introduced into the vacuum chamber is preferably heated and its pressure is raised considerably prior to and for the purpose of introducing the liquid into a vacuum chamber. The vacuum within the chamber is maintained relatively high and when the liquid is thus forced into the highly rarefied atmosphere in a finely divided form, as for instance, by introducing the liquid into the vacuum in a multiplicity of minute, preferably microscopic, capillary streams of flowing oil, the dissolved water and gases in the non-aqueous liquid are caused instantly and automatically to burst into vapor, which is immediately carried off, while the oil is maintained in the liquid state even though in finely divided or film-like condition is recovered.

In that portion of my invention relating to the process of filtering the non-aqueous liquid, I prefer to force the liquid under considerable pressure through fine openings or capillary passages preferably in hard, non-yielding material such as metal for the elimination of the suspended matters and other solids. In particular, I prefer to force the non-aqueous liquid upwardly through the filtering medium whereby sludge or suspended matters entering on the back plate pass through the underside of the filtering medium and will be free from the filtering surface due to the action of gravity. In another aspect of my invention, by forcing the liquid upwardly through the filtering passages and thence causing it to flow in a generally horizontal direction, while particularly under the action of a relatively high vacuum, I am enabled successively and/or simultaneously to effect the evaporation of the moisture content of the non-aqueous liquids to render the liquid anhydrous.

Yet another object of my invention resides in a process for the treatment of electrical insulating oils by forming the same into a liquid film of porous structure by subjecting the liquid to be purified to a relatively high vacuum at the point of film formation and in such a manner that the more volatile impurities will change to their vapor phase before being removed and by so doing will convert a liquid film during formation into a froth-like or porous structure of greatly increased area of exposure and sur-

face contact, all of which is carried out under a high degree of vacuum and with the exclusion of air.

Yet another object of my invention resides in the provision of a method for the breaking up of electrical insulating oils preferably while in a heated condition into a multitude of very fine streams of flowing liquid oil while subjecting the same to a relatively high degree of vacuum and also in causing said streams of flowing liquid oil to be transformed into film-like condition while still subjected to the high degree of vacuum whereby to cause the vaporization of substantially all of the moisture and objectionable gases therefrom.

These and other objects of my invention will be apparent from a perusal of the following specification when taken in connection with the following drawings wherein.

20 Fig. 1 represents an elevation mostly in sections of one form of apparatus for carrying out one form of my improved process;

Fig. 2 represents in plan one of the filtering and moisture-removing elements comprising a metal tape having spaced cross bars on one side thereof;

Fig. 3 is a plan view of the apparatus shown in Fig. 1;

Figure 3a is a detail of parts of the piping system;

Fig. 4 is a side elevation viewed from the right hand side of Fig. 1;

Fig. 5 represents a complete circulating system when the apparatus shown in Fig. 1 is connected to a transformer for the purpose of purifying the oil therein and recovering the dielectric properties thereof;

Fig. 6 is an elevational view of the float-controlled valve mechanism;

40 Fig. 7 is a plan view partly in section of the float-controlled valve, and

Fig. 8 is a sectional elevation taken on the line 8-8 of Fig. 7, looking in the direction of the arrows.

45 The present application is a divisional application of my co-pending apparatus application, Serial No. 302,743 filed August 29, 1928.

In the present application I have selected the described apparatus as one which will accomplish a dual treatment of the non-aqueous liquids, to-wit: an apparatus for rendering the liquid anhydrous and/or also for filtering the same. These operations are separable and distinct and my invention includes these two treatments as distinct, separable and individual processes and as not dependent one upon the other.

In particular, in carrying out the filtering step which involves the process of removing moisture from the liquid, I force the liquid under substantial pressure through a porous or perforated structure whereby to sub-divide the liquid into a multitude of relatively fine flowing liquid streams which are suddenly subjected to a relatively high vacuum, whereby the moisture and other foreign gases in the liquid are caused instantly to burst into vapor and to be automatically removed from the liquid. The liquid itself is by this action and/or its subsequent treatment, transformed into a film-like state, which is continuously subjected to this relatively high vacuum to carry out the substantially complete removal of the moisture and foreign gases which are immediately withdrawn. The thus treated and purified oil is collected for re-use.

By thus forcing the non-aqueous liquid through sufficiently small openings and into the presence of a high vacuum I am enabled also efficiently to remove objectionable solids from the non-aqueous liquid, thus to effect filtration thereof.

I shall describe the filtering process and the process of rendering non-aqueous liquid anhydrous separately. I shall first describe the treatment of the non-aqueous liquid whereby it is forced under pressure through the passages in 10 the porous element which are of size sufficiently minute to filter the liquid.

In carrying out my invention I prefer to use the apparatus shown in the accompanying drawings. In Fig. 2 I have shown a type of a combined filtering and dehydrating element in the form of a ribbon-wound disc 9 comprising a thin metal ribbon 10 wound tightly on a hub 11 and having one side smooth and the other side provided with spaced-apart raised cross ribs 12. This ribbon may be approximately $\frac{3}{8}$ " in width, .0036" thickness and the raised cross ribs may be .0004", the total thickness of the ribbon, including the cross ribs being .004" in thickness. When the tape is wound compactly, each passage may be $\frac{1}{8}$ " in width and .0004" in depth between the edges of the ribbon and from one side of the flat disc filter element 9 to the other side thereof. Such elements may have their dimensions vary, those set forth being by way of illustration of the capillary nature of the minute passages. In varying the dimensions of the grooves, for instance, by rendering the passageway slightly larger, the filtering operation may be altered or even eliminated while preserving that portion of my process relating to the elimination of the moisture and objectionable gases in non-aqueous liquid.

In the formation of the elements 9 for use in the process of filtration to accompany the process of rendering the non-aqueous liquids anhydrous, they should be mounted on hubs 11, soldered and otherwise secured at 13 to the peripheral portions of inverted cups 14. The hubs 15 of the cups are concentric with the hubs 11 and are spaced therefrom as shown in Fig. 1. Each unit comprising the element 9 and the cup 14 has an interior chamber 16 on the entrance side thereof. At the center of the plate 17 is a cylindrical support 18 screw-threaded to receive the lower screw-threaded end 19 of the vertical pipe 20 as shown in Fig. 1. This pipe 20 is provided with a series of perforations or ports 21 which are respectively in communication with the chamber 16 of the individual units. These units are preferably so arranged that their entrance sides face downwardly so that when used for the purpose of filtration the heavier particles of impurities in non-aqueous liquid may fall by sedimentation to the upper sides of the cups 14. It should be understood that fine particles of carbon and other solid impurities may cake on the lower sides during filtration and will act to filter the incoming liquid so long as such caking remains sufficiently porous below the lowermost unit. The flat disc 22 may be mounted in position concentric with the units by reason of the hub 23, which fits over vertical tube or pipe 20. This disc 22 may act as a collector for the impurities which fall by sedimentation from the lower face of the lowermost unit.

When the multiple unit mechanism shown in Fig. 1 is to be cleaned mechanically, impurities may be scraped from the bottoms of the units for collection on the tops of the cups 14 and on the 75

upper surface of the plate 22. Over the upper end of plate 22 is placed a closed cap 24 so as to fit on top of the uppermost hub 15. Screw threaded into the top of the cap 24 is a nut 25 which serves as an abutment adjustable in elevation. A canopy top 26 is provided with an interior central downwardly projecting cylindrical member 27 which may fit over the top of the nut 25 and also over the upwardly extending cylindrical portion 28 of the cap 24. When this canopy top is secured by means of the bolts 29 to the casing 30 and the latter secured by the bolts 31 to the reservoir or tank 32, the whole series of units is rigidly connected to the plate 17 and the latter is bolted by means of the bolts 33 to an opening in the top of the reservoir 32. The reservoir 32 is secured by the bolts 34 to the bed plate 35. It will thus be seen that since the reservoir 32 is secured rigidly to the bed plate 35 and the casing 30 is rigidly bolted to the reservoir 32, the canopy 26 and the plate 27 rigidly connect the mechanism to the tank or reservoir 32.

The chamber 36 is entirely enclosed and is separate from the interior of the tank 32, except through the pores or passageways of the combined dehydrating and filter elements, the chambers 16, the ports 21 and the interior of the pipe 20. It will therefore be evident that when oil or other liquid to be treated is introduced into the chamber 36 from the pipe 37 in Fig. 1 in the direction indicated by the arrow 38 the liquid cannot escape, except as indicated by the upwardly directed arrows under the filter elements 9 and the downwardly directed arrows in the tube 20.

When the liquid to be treated is more or less viscous it may be heated by the heating elements 39, 39 which may be of the electric type with downwardly extending electric heating coils 40, as indicated diagrammatically by the dotted lines in Fig. 1. These heating elements may be placed back of vertical baffle plates 41, 41 or in such positions as to effect thorough mixing of the heated liquid by convection currents.

In Fig. 3 I have shown a pump 42 operated by the electric motor 43. This pump is adapted to pump the liquid to be treated from a pipe 44 into the pipe 45 and out through the pipe 46 to the pipe 37. In a by-pass around the pump 42 is connected a check-valve 47 between the pipes 48 and 49, as shown in Fig. 3^a. This check-valve 47 is adapted to open upwardly from the pipe 48 to the pipe 49 when the pressure in the pipe 37 and therefore in the chamber 36 exceeds a predetermined maximum. This may occur when the filters and dehydrators become so clogged with impurities that the rate of treatment is slowed down considerably. The check-valve 47 in the by-pass around the pump 42 will circulate the liquid back to the entrance side of the pump until the pressure in the chamber 36 is reduced. Therefore, neither the pump 42 nor the motor 43 will become stalled when the pressure in the chamber 36 where the units are located reaches a predetermined maximum.

As shown in Fig. 3, the bed plate 35 is of sufficient area to have mounted thereon not only the reservoir 32 and the closed casing 30, but also the electric motor 43 and the pump 42. By referring to Fig. 5 it will be seen that the pump 42 may be connected by the pipe 44 to the oil reservoir of a transformer 50. When the valve 51 is open the used oil may be pumped through the pipe 44 into the pipe 37 and thence into the closed chamber 36, and when the pump exerts

sufficient pressure the oil will be filtered by the filter elements 9. These filter elements are mounted in multiple, there being ten shown in Fig. 1. The filter elements are immersed in the oil in the chamber 36 and therefore the hydraulic pressure is substantially equal over all of the lower or entrance sides of the filter elements. Such pressure may be approximately one hundred and fifty pounds per square inch and although the flow through each minute passageway 10 is extremely restricted on account of the capillary nature of such passageways, it should be understood that there are a great many of such passageways in each filter element so that in the aggregate a large porous surface is exposed to the liquid pressure. The filtered oil flows simultaneously into and out of all of the chambers 16 at the discharge sides of the filter elements and thence into the tube 20 and down the latter into the reservoir 32.

The same electric motor 43 which drives the pump 42 may also be connected to drive the pump 52 to pump the filtered oil from the reservoir 32 into the pipe 53 and thence into the top of the transformer reservoir 50 when the valve 54 is open. The arrows in Fig. 5 indicate the flow of the oil from the transformer and back to the transformer.

As shown in Fig. 3, the pump 52 is not connected directly to the pipe 53. The dirty oil pump 42 and the clean oil pump 52 may both be mounted to be driven by the motor 43. This low position is particularly desirable for the clean oil pump 52 so that its suction connection through the pipe 55 may always receive priming liquid from the oil in the reservoir 32. In fact the depth of the oil in the reservoir 32 should not fall below that necessary for keeping the clean oil pump 52 primed with oil. This is particularly true when the vacuum apparatus hereinafter described is employed in the oil purification system. The minimum level of the oil in the chamber 32 is indicated by the dotted lines 56 in Figs. 1 and 4. The section pipe 55 will then always be below the minimum level of the liquid in the reservoir 32 and the pump 52 may be continuously operated with the assurance that it will always pump oil from the reservoir 32, as indicated by the dotted arrows in Fig. 4.

The float controlled valve shown in Figs. 1, 6, 7 and 8 will determine whether the oil will flow through the pipe 53 to the top of the transformer or back into the reservoir 32. This float controlled valve so operates that when the depth of the oil in the reservoir 32 is above that indicated by the lines 52, the oil will be pumped to the transformer, whereas when it falls to the depth indicated by the level 56, the oil will be automatically directed back into the reservoir 32.

The clean oil pump 52 is mounted in a pan bracket 57 which is secured to the vertical plate 58 attached to an opening in one side of the reservoir 32. Whether the oil is pumped to the transformer or back into the reservoir 32, it first passes from the pump 52 into the pipe 59 and thence through the opening 60 in the plate 61 which is bolted to the plate 58. Secured to the plate 61 is a manifold 62 having passageways for the flow of the oil, as indicated by the arrows 63, 64 and 65. The port 66 is in communication with the port 60 through the manifold 62. The port 66 is connected directly to the pipe 53.

At the center of the manifold 62, midway between the ports 60 and 66, is a cylindrical valve

67 having diametrical ports 68, 68 for maintaining communication at all times between the ports 60 and 66.

Connected to the stem 69 of the cylindrical valve 67 is a rod 70 at the upper outer end of which is a float ball 71 which is adapted to float in the oil in the reservoir 32. When this float is at the elevation indicated by the dotted lines in Fig. 1 by reason of the high oil level indicated by the dotted lines 72, the valve ports 68 will be in the positions shown in Fig. 8. In the lower portion of the valve 67 is an elongated port 73 and in the bottom of the manifold is a similar port 74. When the depth of the oil in the reservoir falls 15 below the level indicated by the dotted lines 72, the valve 73, 74 tends to open and when the level 56 is reached, the float 71 drops to such a low position that the valve port 73 will be in full registry with the port 74 in the manifold. Then 20 the maximum amount of oil will by-pass from the pump 52 through the pipe 53, port 60, manifold 62, port 68 and ports 73 and 74 back into the reservoir 32, because the port 73 communicates directly with the interior of the reservoir 32. 25 While therefore the valve 67 maintains communication between the ports 60 and 66 at all times, the opening of the ports 73, 74 will establish a by-pass back to the reservoir 32 when the depth of the oil in the latter falls below a predetermined 30 level. When no oil is to be pumped into the transformer, the valve 54 may be closed and nevertheless the clean oil pump may continue its operation when the by-pass is open through the ports 73 and 74. So also when the valve 54 is 35 closed, the by-pass illustrated in Fig. 3a will permit continued operation of the dirty oil pump 42 without stalling the same. When, however, filtering operations continue with the valve 51 open and the valve 54 closed, the closing of the 40 ports 73 and 74 by the level of the liquid reaching that designated 72 in Fig. 1 will automatically stall the pump 52 and stop the electric motor 43 which is protected by the usual electric circuit breaking devices. It will also be seen that even 45 when the valve 54 is kept open, the depth in the transformer reaches the point where no more oil can be pumped into the same, the clean oil pump 52 will be stalled when the depth of the oil in the reservoir 32 reaches the level 72 where the valve 50 50 55 59 73, 74 will be closed. However, it is intended that the amount of oil in the reservoir and in the transformer 50 shall be proportioned so that the pumping system may go on continuously to constantly circulate the oil so long as the electric current is supplied to the motor 43 to operate the same. The nature of the liquid being filtered will largely determine the rate of filtration and where there are considerable solid impurities in the liquid being filtered, the filter elements will tend 60 to clog gradually and the rate of filtration decrease, which will tend to decrease the amount of filtered oil supplied to the reservoir 32. It therefore becomes desirable to provide the automatic float control valve to by-pass the oil from 65 the clean oil pump 52 back to the reservoir 32 when the depth of the liquid in the reservoir tends to fall toward the minimum permissible depth indicated by the dotted line 56.

When desired, the box 76 may be detached and 70 removed and the vacuum pump removed therefrom so as to permit renewal of the calcium chloride. As shown in Figs. 1 and 4, the suction port 77 is at the upper end of the vertical passage-way 90 at one side of the box 76 so that the water 75 vapor may be compelled to pass down through

the port 91 and then up through the calcium chloride in the box 76.

The vacuum pump 75 may also be operated as a blower by closing the valve 83 and opening the valve 84 so as to permit the pipe 92 which is open to the atmosphere to act as a suction pipe. When the valve 81 is closed and the valve 82 is open, air may be drawn by the pump 75, as indicated by the arrows 93, 94 and 95, from the atmosphere and blown into the chamber above the liquid in the reservoir 32 and thence upwardly through the pipe 20 into the various chambers 16 to produce sufficient pneumatic pressure through the multiplicity of pores or passageways in the laminated elements to force the caked solid impurities from the bottoms of the filter elements from which such impurities will drop on the tops of the cups 14. At intervals, depending upon the amount of solid impurities filtered from the liquid being treated, the pump 75 may be operated to flush the filter units with compressed air to force the solid caked impurities from the entrance sides of the filter elements and thus restore the efficiency of the filtering apparatus until such time as it may become desirable to remove the canopy 26 and the housing 30 to permit mechanical cleaning of the filtering units.

The process whereby moisture and other deleterious gases are automatically removed from the liquid to be treated is accomplished, in principle, by forcing the liquid to flow under pressure in relatively fine streams or in sub-divided condition, and while in such state, subjecting it to the action of a relatively high vacuum whereby the moisture will burst into vapor and be released from the liquid.

Referring more in particular to a method for accomplishing this function, it will be apparent that particularly in reference to oil used for electrical insulation purposes minute particles of water condensed from the atmosphere will collect in the oil used to cool and insulate electrical apparatus such as electric windings of high voltage transformers and it is important to remove such moisture or water from the oil, since even microscopic traces of moisture in transformer oil seriously interferes with its dielectric strength. I have, therefore, provided an improved method for so treating the oil by applying a vacuum to the discharge side of the porous elements 9 through which the oil is forced in minute flowing streams under pressure, so as to remove the water from the oil and preferably without interfering with the operation of the transformer, and without necessitating its being shut down or disconnected from a high tension system. In other words, the oil in the transformer may be treated to restore its dielectric strength without shutting down a transformer, or disconnecting it from the system in which it is being used.

For this purpose a vacuum pump 75 is mounted on the box 76, which in turn is mounted in an opening in the reservoir 32 and connected thereto so as to be hermetically sealed. The box 76 is adapted to contain water absorbing material, such as calcium chloride, and is provided with a suction port 77 in direct communication with the upper interior portion of the reservoir 32. A pipe 78 is connected between the top of the vacuum pump 75 to the atmosphere, as indicated by the arrow 79. A by-pass pipe 80 is connected between the pipe 78 and the interior upper portion of the reservoir 32. When the valve 81 is open and the valve 82 is closed and the valve 75

83 is also open and the valve 84 is closed, the vacuum pump may be operated to apply the vacuum, as indicated by the downwardly curved arrows in the tube 21 and the arrows indicated by the reference numbers 86, 87 and 88. The vacuum pump 15 may be operated by the electric motor 89 shown in Fig. 4. While the vacuum is applied to the upper surface of the oil in the reservoir 32, it is not there where the water is entirely withdrawn from the oil, although if there is any water still in the oil in the reservoir 32 it may be withdrawn therefrom to some extent by the vacuum in the space above the liquid level.

The pressure acting at one end of the openings 15 in the elements 9 will force the liquid oil therethrough and the high degree of vacuum acting on the other end of these openings or passages will tend to pull the liquid oil therethrough or cut down the frictional resistance of the walls to the 20 passage of the oil or liquid therethrough. In effect, the vacuum will penetrate a considerable distance along the passage formed in elements 9 and will operate as a means for volatilizing or vaporizing the moisture and the volatile impurities. As these minute flowing streams of liquid 25 arrive at the outer surface of the elements, and while under the influence of the high degree of vacuum and to the exclusion of air, the streams of flowing liquid will form continuously in film-like formation on the upper surfaces of the elements and in such a manner that the water, 30 moisture or other undesirable volatile impurities will burst into vapor and will automatically separate from the liquid oil under the action of the vacuum pump. In particular, when the liquid oil emerges from the porous elements, it spreads 35 in a thin film and it is the application of the vacuum in the chamber 16 that is most effective in causing the water and other volatile constituents of the oil to burst into vapor. When a high 40 vacuum is produced and the temperature of the oil has been raised by the heating elements 39 the boiling point of the microscopic traces of moisture and water has been so lowered by the 45 application of the vacuum that all of the small traces of water in the oil, as soon as it emerges from the passages of the porous element into the chamber 16 will vaporize and cause frothing so as to greatly increase the film surface of the 50 oil and decrease the thickness thereof, thus exposing a maximum area and quantity of oil to the vacuum to remove even microscopic traces of the water from the oil and thus restore the insulating properties of the oil or its high dielectric 55 strength. Thus the water traces will be removed from the oil with the result that when it is pumped back to the transformer it will be in very excellent condition as to its desirable qualities and particularly as to its insulating properties and high dielectric strength.

It should be noted that while the method above described is particularly adapted for dehydrating electrical insulating oils, such as those used in electrical transformers, to restore the electric insulating and dielectric properties thereof, it 60 may have a general application in that a more volatile ingredient may be removed from a mixture of liquids by the application of the vacuum producing apparatus. The multiplicity of minute 65 passageways in each element produces flowing liquid streams which are further sub-divided into film form at the upper ends of such streams at the upper surfaces of the elements for flow therefrom by gravity through the ports 21 into the tube 70 20. By application of the vacuum to the dis-

charge sides of the elements the smallest traces of water may be removed from the insulating oil, and as before stated, the preheating by the four electric heaters 39 shown in Fig. 3 facilitates not only the removal of the solid impurities, but also 5 all of the water from the oil.

Obviously those skilled in the art may make various changes in the details and arrangement of parts without departing from the spirit and scope of the invention as defined by the claims hereto 10 appended and I wish therefore not to be restricted to the precise arrangement herein disclosed.

I do not herein claim the novel apparatus for treating liquids in the manner disclosed herein since the same forms the subject matter of my 15 application Ser. No. 302,743, filed August 29, 1928, of which this application is a division. Said application was issued as Patent No. 1,951,809, dated March 20, 1934.

Having thus described my invention, what I 20 claim as new and desire to secure by Letters Patent of the United States is:

1. The process of removing moisture and gases from oil which comprises forcing the oil under super-atmospheric pressure upwardly through 25 capillary passages in a tank maintained at sub-atmospheric pressure to release the moisture and gases from the oil, collecting the oil and separating the gases therefrom, and flowing the oil toward the bottom of the tank while exposed to the 30 reduced pressure in the tank.

2. The process of removing moisture and gases from oils comprising raising the pressure of the oil substantially above atmospheric pressure and utilizing said pressure for forcing it upwardly in 35 very fine streams through capillary passages at a temperature below 160 degrees Fahrenheit into a rarefied atmosphere maintained constantly under a high vacuum to release the moisture and gases from the oil, and separating the moisture and 40 gases from the oil.

3. The method of dehydrating oils which consists in forming a multiplicity of minute streams of liquid oil and directing the same upwardly 45 while subjecting the same to a relatively high degree of vacuum, flowing said streams laterally into film-like form while subjected to said vacuum, causing the dehydrated oil to flow from such surface films by gravity while removing the released moisture.

4. The method of dehydrating oil which consists in forming a multiplicity of minute streams of liquid oil and directing the same upwardly to a plurality of superposed spaced-apart surface films, applying a vacuum simultaneously to all 55 of such surface films to vaporize the water in the liquid and effect frothing thereof, and continuously permitting the dehydrated liquid to flow from such surface films by gravity while supplying additional hydrated liquid to the bottoms of 60 said surface films.

5. The method of increasing dielectric strength of insulating oil, which consists in filtering the oil by means of a multiplicity of pores through 65 which the oil flows upwardly and spreading the oil into a thin film at the upper limit of said flow, and applying a vacuum to such upper film to remove microscopic traces of water from the oil by volatilization and evaporation of the water in the oil as it emerges from such pores into said thin film and thereby increase the dielectric strength and insulating properties of such oil.

6. The method of dehydrating oils used for electrical insulation, which consists in forming a 75

- thin oil film on a horizontal supporting surface by feeding the same with a multiplicity of closely adjacent minute streams of oil of microscopic dimensions in cross-section and flowing upwardly to continually replenish the film with oil to be dehydrated, and applying a vacuum to such continually forming thin film to effect volatilization of the water in the oil and the frothing of the oil in the film to effect dehydration of the oil.
- 10 7. The method of removing impurities from electrical insulating oils which consists in filtering the oil while causing it to flow upwardly in a multiplicity of closely adjacent minute streams, spreading out the oil at the upper ends of said minute streams into a thin film on a horizontal supporting surface, and applying a vacuum to such film to effect volatilization of the water in the oil to remove such water simultaneously with the continuation of such filtration of the oil.
- 15 8. The method of treating oils which comprises forcing the liquid oil under pressure upwardly through capillary passages of sufficiently minute cross section to remove solid impurities, applying a relatively high vacuum to the discharge end of such capillary passages to cause

moisture in the oil to burst into vapor, removing the vapor and collecting the oil.

9. The herein described process of treating oils which comprises forcing the heated liquid oil under substantial pressure upwardly through capillary passages to remove suspended solids, and subjecting the oil at the discharge side of said passages to relatively high vacuum to release moisture therefrom.

10. The herein described process of treating oils which comprises forcing liquid upwardly through passages of such small cross section so as to sub-divide the oil into microscopic flowing liquid streams while subjecting the flowing streams to the action of a high vacuum.

11. The process of treating oils which comprises forcing the oil under super-atmospheric pressure upwardly through capillary passages of sufficiently minute cross section to remove solid impurities, into a vacuum chamber where moisture vapor is withdrawn from the oil, and forcing cleaning fluid through said passageways downwardly in the opposite direction whereby to clean said passageways.
